Edgar P. Tates, Jr.

UNITED STATES PATENT OFFICE.

PAUL G. BRUNZEL, OF NEW YORK, N. Y.

PROPELLING MECHANISM.

1,312,679.

Specification of Letters Patent. Patented Aug. 12, 1919.

Application filed September 10, 1918. Serial No. 253,392.

To all whom it may concern:

Be it known that I, PAUL G. BRUNZEL, a citizen of the United States, and residing at New York, in the county of New York and State of New York, have invented certain new and useful Improvements in Propelling Mechanisms, of which the following is a specification, such as will enable those skilled in the art to which it appertains to 10 make and use the same.

This invention relates to mechanisms for propelling row boats, canoes, motor boats and the like, and the object of the invention is to provide an apparatus of this class 15 which is adapted to be manually operated and controlled; a further object being to so mount the apparatus in connection with the boat as to permit of the movement thereof into and out of the water or into operative 20 and inoperative positions; and a still further object being to provide a propelling mechanism of the class and for the purpose specified which is simple in construction and operation and efficient in use; and 25 with these and other objects in view the invention consists in an apparatus of the class and for the purpose specified, constructed and operating as hereinafter described and claimed.

30 The invention is fully disclosed in the following specification, of which the accompanying drawing forms a part, in which the separate parts of my improvement are designated by suitable reference characters in 35 each of the views, and in which:

Figure 1 is a sectional side view of the rear end of a boat showing my improvement applied thereto and in position for use;

Fig. 2 a plan view of the construction as 40 shown in Fig. 1;

Fig. 3 a partial section on the line 3—3 of Fig. 1 and on an enlarged scale;

Fig. 4 a diagrammatic view illustrating four different positions of the propeller 45 member employed during one complete revolution thereof;

Fig. 5 a view similar to Fig. 2 but showing two propeller members mounted in the rear end portion of a boat;

Fig. 6 a view looking in the direction of the arrow 6 of Fig. 5 with part of the construction broken away; and,

Fig. 7 a view similar to Figs. 2 and 3 but showing a modified form of gearing 55 which I employ.

In the practice of my invention, as shown in Figs. 1 to 4 inclusive, I hinge to the back 10 of a boat 11 as shown at 12 a backwardly directed bracket plate 13, which is adapted to swing inwardly into the boat on the hinge 12. 60

The bracket plate 13 is provided adjacent to its free end with an aperture 14 through which passes a sleeve 15 to the upper end of which is secured a crank 16. The crank 16 and sleeve 15 are held against vertical movement in the plate 13 by a collar 17 secured to said sleeve below said plate. 65

A bent shaft 18 is rotatably mounted in the sleeve 15 and provided at its lower end with an offset portion 19 upon which is rotatably mounted a sleeve 20, the upper end of which is connected with the sleeve 15 through a universal joint construction 21, comprising yoke-shaped head members 22 70 and 23 mounted on the adjacent ends of the sleeves 15 and 20 respectively, which head members are pivoted to an annular ring 24 mounted on the shaft 18 where it is bent as shown at 25 in Fig. 3 of the drawing. 75

To the lower end portion of the sleeve 20 is secured the shank 26 of a propeller member 27 having a blade or head portion 28, as shown in Fig. 1 of the drawing.

Secured to the upper end of the shaft 18 80 above the crank 16, as shown at 29, is a gear 30 and another gear 31 is rotatably mounted in the free end portion of the crank 16 and a lever 32 is pivoted to a stud 33 on the top of the gear 31, as shown at 34, and 85 said lever is also provided with a hand piece 35, whereby the same may be manipulated to rotate the crank 16 as will be readily understood.

From the foregoing description, the operation will be readily understood when taken in connection with the accompanying drawing and the following statement. When the crank 16, lever 32 and propeller member 27 are in the position shown in Figs. 1 and 2, and it should be desired to propel the boat 11 forwardly, or in the direction of the arrow α of Fig. 4, this is accomplished by pushing backwardly upon the lever 32 to rotate the crank 16 in the direction of the arrow α^2 of Fig. 4, and after moving said crank one-eighth of a revolution, or from the position indicated at y , Fig. 4, to that indicated at y^2 in dotted lines in said figure, the blade 28 of the propeller member 27 will 100 105 110

move from the position shown at x^3 in Fig. 4 to that shown at x^4 in said figure and will also be rotated by the gears 30—31 to change the position thereof, as illustrated in said figure. When the crank has made one-quarter of a revolution or brought into the position shown at y^3 in Fig. 4, the blade 28 will assume the position shown at x^5 in said figure, and when the crank reaches the position shown at y^4 the blade will assume the position shown at x^6 , and when a complete half revolution, or when the crank is in the position shown at y^5 , the blade 28 will again assume the position shown at x^3 in Fig. 4.

In short, at each complete revolution of the crank 16, the propeller member 27 of the blade 28 thereof will make two complete revolutions and be oscillated in each of such revolutions in such manner that during the backward stroke, or the stroke from the position shown at x^4 to that shown at x^6 , or the power stroke, the face of the blade 28 will have its full area against the body of water to produce the greatest possible power, but in the forward stroke of said propeller member, or the stroke of the blade from the position shown at x^6 to that shown at x^4 , said blade will cut through the water and have no retarding or dragging action.

The above operation of oscillating the propeller member during its revolutions is produced by the combined action of the gears 30 and 31 and the rotation of the crank 16 by the lever 32 as is also the rotary movement of the propeller member 27.

The lever 32 as shown in Figs. 1 and 2 of the drawing is designed to be manipulated forwardly and backwardly by a single operator, but it will be understood that by elongating or extending the lever 32, as indicated in dotted lines in Fig. 1, and providing other hand pieces 36 for said lever, a plurality of persons may manipulate said lever to operate the propeller member 27.

In Figs. 5 and 6 of the drawing, I have shown two of my propeller mechanisms mounted at the rear end of the boat 11, said mechanisms being precisely the same as that shown in Figs. 1 to 4 inclusive, but instead of mounting the same in connection with the plate 13 they are connected with the free end of the levers 37, pivoted to the sides of the boat 11 as shown at 38 and the rear ends 39 of which are held against upward movement by a keeper 40 clearly shown in Fig. 6. With the lever mounting for the propelling mechanisms as shown in Figs. 5 and 6, the same may be swung upwardly to bring the propeller member 27 out of engagement with the water whenever desired.

Both of the propeller mechanisms may be controlled by a single operator by grasping the hand pieces 35 of the levers 32 in each hand and moving said levers forwardly

and backwardly alternately, or said levers may be extended and a number of hand pieces connected therewith, whereby two or more operators may control or manipulate each of said propeller mechanisms.

In Fig. 7 of the drawing, I have shown a modified form of gear construction which is substituted for the gears 30 and 31 and consists in providing elliptical gears 41 and 42, the gear 41 being substituted for the gear 30, while the gear 42 is substituted for the gear 31 and the function of these gears is to increase the power at which the propeller member 27, or the blade 28 thereof is driven during the power stroke, or in the movement of the propeller member 27 from the position shown at x^4 to that shown at x^6 in Fig. 4.

From the foregoing it will be noted that the principle of my invention resides in the provision of a propeller member which is preferably mounted to be swung into and out of coöperation with the water and is provided with means whereby it may be rotated as well as oscillated in its rotary movement, and further with means for rotating the propeller member at a greater number of revolutions than the element which drives the same, and while I have shown certain details of construction for carrying my invention into effect, it will be understood that various changes in and modifications of these details of construction may be made, within the scope of the appended claims, without departing from the spirit of my invention or sacrificing its advantages.

Having fully described my invention, what I claim as new and desire to secure by Letters Patent, is:—

1. A propelling mechanism of the class described, comprising a propeller member, means for rotating said member, and means for giving said member a rotary oscillatory movement when rotated.

2. A propelling mechanism of the class described, comprising a propeller member, a crank connected with said propeller member by means of a universal joint whereby said propeller member may be rotated, and means for oscillating said propeller member when rotated by said crank.

3. A propelling mechanism of the class described, comprising a propeller member, a crank connected with said propeller member by means of a universal joint, means for operating said crank to rotate said propeller member, and means for oscillating said propeller member in the rotation thereof.

4. A propelling mechanism of the class described, comprising a propeller member, a crank connected with said propeller member by means of a universal joint, means for operating said crank to rotate said propeller member, and means for oscillating said propeller member in the rotation thereof, where-

by the propeller member will be rotated at a greater number of revolutions than said crank.

5. A propelling mechanism of the class described, comprising a propeller member, a crank, means for universally connecting said crank to said propeller member, a bent shaft mounted within said last named means, a gear secured to one end of said shaft, another gear mounted on the free end portion of the crank and in operative connection with said first named gear, and means for operating the crank to rotate said propeller member and to oscillate it in such rotary movement.

6. A propelling mechanism for boats, comprising a propeller member, a crank, means for universally connecting said crank to said propeller member, a bent shaft mounted within said last named means, a gear secured to one end of said shaft, another gear mounted on the free end portion of the crank and in operative connection with said first named gear, means for operating the crank to rotate said propeller member and to oscillate it in said rotary movement, and means

for movably supporting said mechanism in connection with a boat.

7. A propeller mechanism of the class described comprising a movable supporting member, a shaft rotatably mounted in said member, a propeller member movably mounted on said shaft, and means for operating said propeller member and said shaft to give said propeller member a rotary and oscillatory movement.

8. A propeller mechanism of the class described, comprising a support, a propeller member rotatably mounted in said support, and means involving a gear construction for rotating said propeller member at a greater speed than said means and for oscillating said propeller member in the rotation thereof.

In testimony that I claim the foregoing as my invention I have signed my name in presence of the subscribing witnesses this 7th day of Sept. 1918.

PAUL G. BRUNZEL.
